UNITED STATES PATENT OFFICE.

PETER P. QUIRIN, OF ST. CLAIR, PENNSYLVANIA.

HYDRANT.

SPECIFICATION forming part of Letters Patent No. 341,687, dated May 11, 1886.

Application filed November 9, 1885. Serial No. 182,198. (No model.)

To all whom it may concern:

Be it known that I, PETER P. QUIRIN, a citizen of the United States, residing at St. Clair, in the county of Schuylkill and State 5 of Pennsylvania, have invented certain new and useful Improvements in Hydrants; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 A main object of this invention is to enable the body of the hydrant, together with the valves and fittings thereof, to be readily detached from the water-supply pipe, and to be removed for repairs and cleaning without involving the necessity of digging up the ground. This general object has hitherto been accomplished; but by the construction and arrangement involved in this invention the desired 20 result is achieved in a novel and efficient manner.

The general construction of this improved hydrant includes a cylindrical casing, which is permanently sunk into the ground, and to which the water-supply pipe is permanently 25 secured, a hydrant-body (that portion of the hydrant which is above ground) which is removably bolted to the cylindrical casing, and a depending skeleton frame permanently secured to or forming an integral part with the 30 hydrant-body, which supports the valves, valve-operating mechanism, and water-discharge pipe, and which, when the hydrant is in operative position, is inclosed within the cylindrical casing, the bottom reaching to or 35 nearly to the bottom of said casing, whereby a connection is formed between the water-supply and water-discharge pipes.

In addition to this general construction the invention includes means for draining and 40 ventilating the cylindrical casing, a novel connection between the water-supply and water-discharge pipes, and an improved construction of cut-off valve and waste-valve for draining the water-supply pipe, to prevent the same 45 from freezing.

The invention is illustrated in the accom-

panying drawings, in which Figure 1 is a side view of the hydrant complete. Fig. 2 is a side view of the hydrant-body and parts attached thereto removed from the cylindrical 55 casing. Fig. 3 is a side view, the lower part being shown partly in section, of the cylindrical casing. Fig. 4 is a cross-section of the hydrant. Fig. 5 is a side view of the valve-casing and the pipe-connections detached. Fig. 6 is a central longitudinal section thereof. Fig. 7 is a section of the draining valve mechanism, the section being in a plane indicated by the line 7 7 in Fig. 8; and Fig. 8 is a horizontal section in a plane indicated by the line 65 8 8 in Fig. 7.

A is the cylindrical casing, which is permanently sunk into the ground, with its top extending just above the surface of the ground, and it is provided with an upper annular 70 flange, a, at the top thereof, and at its lower end with side flanges, b b. A bottom plate, B, is bolted to the casing A by bolts c c, which pass through the flanges b b on the casing and similar flanges, d d, on the bottom plate. A 75 water-supply-pipe fitting, C, is secured to the bottom plate within the casing. This fitting has a horizontal branch, e, which extends out through an aperture, f, in the lower part of the casing, which branch connects with a wa- 80 ter-main, and a vertical branch, g, which communicates with the water-discharge pipe. This fitting C is formed with a cylindrical projection, h, on its bottom, which fits into a recess or aperture formed in the bottom plate, B, whereby the fitting is held accurately in its proper 85 position. This fitting is also provided with side flanges, i i, by which it is firmly secured to the bottom plate by bolts j j, which extend through the bottom plate. 90

The hydrant-body D is provided at its lower end with an annular flange, k, and when the hydrant-body is placed in position above the cylindrical casing the flange k is located just above the flange a at the top of the casing. 95 Short bolts l l, passing through these two adjacent flanges, serve to secure the hydrant-body to the casing. The flange a being just above the surface of the ground, easy and ready access may be had to the bolts l l, to remove the same, and so detach the hydrant-body from the casing. 100

Depending from the hydrant-body, and either rigidly secured thereto or formed integrally therewith, is a skeleton frame consisting of two straight arms, E E, which extend downward parallel with each other, and are connected together at the bottom by an annular supporting-plate, F. When the hydrant-body is secured to the casing, these arms extend down within the casing, and reach nearly down to the supply-pipe fitting C. These arms are elliptical in cross-section, as shown in Fig. 4. G is the valve-casing, which is formed with flanges m m, by which it is secured by bolts n n to the annular supporting-plate F. To the valve-casing are connected the valve-operating rod H, which extends upward between the arms E E and through the hydrant-body to the handle I at the top of the hydrant-body, and the water-discharge pipe J, which extends in a similar manner to the nozzle K. The valve-casing is formed on its bottom with a cylindrical projection, o, which fits into and extends through an aperture formed in the supporting-plate F, whereby it is accurately held in proper position. A downwardly-projecting nozzle, L, communicating with the interior of the valve-casing and extending from the bottom of the projection o, fits into the vertical branch g of the supply-pipe fitting. Surrounding the nozzle L, and seated against the shoulder formed between the nozzle and projection o, is an elastic packing-ring, p, which rests upon the upper surface of the supply-pipe fitting when the nozzle is inserted therein, thus making a water-tight joint. When the hydrant-body is placed in position on the casing, the nozzle L is brought into proper position over and within the supply-pipe fitting, and by screwing up the bolts l l, which secure the hydrant-body and casing, the elastic packing-ring p is preferably held partly within the aperture in the supporting-plate F, the projection o not extending entirely through said plate. This arrangement prevents the spreading of the ring under the pressure to which it is subjected. There is no necessity of the nozzle L fitting tightly in the supply-pipe fitting, and it preferably fits loosely therein. The aperture f at the lower end of the casing, through which the horizontal branch of the supply-pipe fitting extends, is made of a sufficient size to constitute a drainage-port to carry off any water which may collect in the casing, as happens when the discharge-pipe is drained, as will hereinafter appear. Above this aperture f is a second aperture, f', in the casing, which constitutes a ventilating-opening. There is always more or less of an opening left between the flange a on the casing and the flange k on the hydrant-body, so as to leave an air-passage above ground between them, and through this opening, the interior of the

casing, and the aperture f' a ventilating-passage is formed for the warm vapors arising from the ground, which, passing through the casing, materially increase the temperature within the casing and reduce the liability of the freezing of the water within the casing. By this arrangement of the casing, hydrant-body, and fittings it will be seen that the outer surface of the casing is the only part which comes in contact with the earth, the connecting-bolts being entirely above ground, and all the other parts being within and protected by the casing and hydrant-body. The hydrant-body is easily separated from the casing by simply loosening the bolts connecting the flanges, and then all the valve-fittings are at once removed from the casing, and access can be had to all the parts for repairing and cleaning. The depending skeleton frame not only enables ready access to the valve fittings, but is also much lighter and more economical in manufacture than if it were a closed tube. This depending frame is a very important feature of this invention.

In order to obtain a water-tight connection between the water inlet and outlet pipes, considerable force is applied to the fastening-bolts l l, and this strain is borne by the depending frame, instead of by the water-discharge pipe. This arrangement also permits the valve-operating rod to be entirely separate from the water-discharge pipe, which is in all cases desirable. The water-supply fitting cannot get out of order, on account of being rigidly and permanently bolted to the bottom of the casing, and to clean it, if necessary to do so, is easily accomplished by turning on the water before the hydrant-body is inserted into the casing. In this connection the advantage of the described coupling between the valve-casing, nozzle, and the water-supply fitting is most clearly apparent. In those cases where a screw-threaded coupling is used the moment that the parts are first brought together the discharge of water is shut off, and any mud or sand within the outer casing is at once deposited about the coupling, injuring the threads of the screws and preventing the parts being screwed tightly together. With the coupling here described there are no screw-threads, and as the nozzle fits loosely in the supply-casing the discharge of water will not be entirely shut off until the packing-ring is seated squarely against the supply-casing.

The valve-casing proper contains a main valve-chamber, M, which communicates directly with a passage, N, extending through the nozzle L, and a branch chamber, O, communicating with the valve-chamber at the lower part thereof, and which also communicates with the discharge-pipe J, which fits therein. In this valve-chamber the main cut-off valve P works. This valve slides up and down within the valve-chamber, and is provided on its under side with an elastic packing-ring, q, which forms a water-tight joint when the valve is brought against the valve-

seat formed at the bottom of the chamber. The valve when, down thus, closes the passage N, leading from the water-supply pipe, and shuts off communication with the discharge-pipe chamber O. When the valve is raised from its seat, the passage N is uncovered, and communication is then established between the water-supply and discharge pipes. The valve is formed on its upperside with a guide-plate, 5 Q, one side of which slides between projecting ways r r, formed on the side of the valve-chamber, and the other side of the valve is formed with a groove, s, which slides upon a similar way, r', formed on the opposite side of 10 the valve-chamber. The valve is thus held from turning, and constitutes a slide-valve. The upper end of the valve-chamber is closed by a cap, R, which is screwed thereto. 15

Rotatively attached to the valve is the valve-20 stem S, which is screw-threaded, and passes through a female-screw-threaded passage extending through the cap R. To the upper end of this valve-stem is secured a coupling, T, which connects the valve-stem to the valve-25 operating rod H. This coupling is formed with a rectangular aperture, in which the squared lower end of the operating-rod fits. This, while insuring the rotation of the valve-30 stem when the rod is rotated by the handle I, permits the valve-casing to be easily separated from the operating-rod when desirable. The rotation of the valve-stem screws the same up and down in the cap R, thus raising and lowering the valve P. As the cap R is rarely disturbed, its threads render it sufficiently watertight; but through constant use the threads of the valve-stem will not always remain watertight. To prevent any leakage from this 35 source the cap R is formed on its top with a tubular projection, U, exteriorly screw-threaded, through which the valve stem passes. Fitting over this projection is a female-screw-threaded thimble, V, which encircles the valve-stem. Within this thimble, and encircling the 40 valve-stem, any suitable packing material, t, is placed, and upon screwing the thimble down upon the projection U this packing is compressed and packs the valve-stem. 45

When the hydrant has been used and the 50 water again shut off by closing the cut-off valve P, the water-discharge pipe is left full of water, which, unless drained off, would freeze in cold weather and burst the pipe. To drain off this water the following mechanism is 55 adopted: The valve P does not entirely fill the valve-chamber, but is of a diameter less than the diameter of said chamber. The space in the chamber above the valve is thus at all times in communication with the discharge-pipe. To drain off the pipe and the 60 valve-chamber a waste-port, u, is cut in the wall of the chamber, which establishes communication with the outer space within the casing A. This port is located in the wall of 65 the chamber between the projecting ways r r, between which the valve-extension Q slides. In order that this port may not be open when

the hydrant is in use, an elastic waste-valve, W, is carried by the projection Q. This waste-valve, when the main valve is seated, is 70 just below the waste-port, thus leaving the same open. When, however, the main valve is raised to turn on the water, the waste-valve is at once brought over the waste-port, thus closing the same and keeping it closed while 75 the hydrant is in use. As this waste-valve is preferably held, as shown, between arms on extension Q, which prevent the vertical displacement, the upper arm, w, is provided with a groove or passage, x, on its face, which 80 establishes communication with the port u when the main valve is closed. Lateral displacement of the waste-valve is prevented by the projecting ways r r. The water passing through the waste-port runs into the interior 85 of the casing A, and from thence escapes into the ground through the apertures.

These improvements, though designed especially for domestic hydrants, are equally applicable to fire-plugs and all cases where 90 water under pressure is to be used and shut off.

I claim as my invention—

1. A hydrant-casing permanently sunk into the ground and a hydrant-body removably secured thereto, in combination with a depending skeleton frame secured to said hydrant-body, said frame being composed of two rigid parallel arms connected together by a plate at their lower ends, which frame is inclosed within said casing when the hydrant is 100 in position for use, a valve-casing supported by the bottom plate of said depending frame, and a valve operating rod and a water-discharge pipe extending upward from said valve-casing through said inclosing-casing and 105 through said hydrant-body, substantially as set forth.

2. A hydrant-casing which is permanently sunk into the ground and a water-supply fitting centrally secured within and to the bottom of said casing, in combination with a hydrant-body removably secured to said casing, a depending frame secured to said body and extending down within, but unattached to, said casing, a supporting-plate secured to the 110 lower end of said frame, said plate having a central opening, a valve-casing secured to the upper surface of said plate, a downwardly-projecting nozzle upon said valve-casing, which extends through the opening in said supporting-plate and enters said supply-fitting, and a valve-rod and water-discharge pipe connected with said valve-casing and extending upwardly through said hydrant-body, substantially as set forth.

3. A hydrant-casing provided with a bottom plate having an aperture or recess in the center thereof and a water-supply fitting secured to said bottom plate and having a cylindrical projection which fits in said aperture 120 or recess, in combination with a hydrant-body removably secured to said hydrant-casing, depending arms secured to said body, which reach nearly to the bottom of said hydrant-

casing, a supporting-plate secured to the lower ends of said arms, said plate having a central opening therein, and a valve-casing secured to said supporting-plate, said casing having a 5 downwardly-projecting nozzle which extends through said aperture in said supporting-plate and enters said water-supply fitting, substantially as set forth.

4. A hydrant-casing, a water-supply fitting 10 carried thereby, said fitting having an upwardly-extending open branch, and a hydrant-body removably secured to said casing, in combination with a depending frame attached to said body and extending downward into 15 said casing, a supporting-plate carried at the lower end of said frame, said plate having a central opening, a valve-casing secured to the upper surface of said supporting-plate, said casing having a downwardly-extending pro-

jection, *o*, which fits in the opening in said 20 supporting-plate, but does not extend entirely through said opening, a downwardly-extending nozzle forming part of said valve-casing, which extends below said projection *o* and enters the vertical open branch of the supply- 25 fitting, and a packing-ring surrounding said nozzle and seated against the projection *o* and partly held within the opening in said supporting-plate, which packing-ring renders water-tight the joint between said valve-casing 30 and supply-fitting, substantially as set forth.

In testimony whereof I affix my signature in presence of two witnesses.

PETER P. QUIRIN.
